UNITED STATES PATENT OFFICE.

THOMAS H. HALE, OF FAYETTEVILLE, NORTH CAROLINA.

SAFETY DEVICE FOR LOCOMOTIVES.

No. 854,290.

Specification of Letters Patent.

Patented May 21, 1907.

Application filed September 20, 1906. Serial No. 335,487.

To all whom it may concern:

Be it known that I, THOMAS H. HALE, a citizen of the United States, residing at Fayetteville, in the county of Cumberland and State of North Carolina, have invented a new and useful Safety Device for Locomotives, of which the following is a specification.

This invention relates to safety appliances for locomotives, and other railway rolling stock and has for its object to provide improved means for preventing wreckage of the locomotive and attached cars in case of collision with a train traveling in the opposite direction or with cars standing on an open switch or side track.

A further object of the invention is to provide a spring buffer or cushioning member secured to the boiler-front and movable to projected position in the path of the approaching train thereby to deaden the jar of shock incident to the impact of the train and thus prevent injury to the cars and passengers.

A further object is to provide a pair of auxiliary buffers disposed one on each side of the main buffer and operated simultaneously from the engineer's cab.

A further object of the invention is to generally improve this class of devices so as to increase their utility, durability and efficiency.

With these and other objects in view the invention consists in the construction and novel combination and arrangement of parts hereinafter fully described, and illustrated in the accompanying drawings, it being understood that various changes in form, proportions and minor details of construction may be resorted to within the scope of the appended claims.

In the accompanying drawings forming a part of this specification: Figure 1 is a side elevation of a locomotive provided with a safety-appliance constructed in accordance with my invention. Fig. 2 is a top plan view of the same.

Similar numerals of reference indicate corresponding parts in all of the figures of the drawings.

The improved device is principally designed for reducing the jar or shock incident to the collision of locomotives and other railway rolling stock and by way of illustration is shown applied to a locomotive of the ordinary construction in which 5 designates the

cab, 6 the boiler and 7 the boiler-front, or head.

Secured to the boiler-front or head 7 in any suitable manner as by bolts, rivets or similar fastening devices 8 is a casing or housing 9 preferably cylindrical in shape, as shown and provided with a cap or closure 10.

Arranged within the casing 9 and secured in any suitable manner to the cap 10 is an extensible member or buffer preferably in the form of a coil spring 11, the latter being movable to operative or projective position in the path of an approaching train thereby to receive the impact of locomotives and thus prevent wreckage of the cars and consequent injury to the passengers.

Arranged within the coils or convolutions of the springs 11 and secured in any suitable manner to the cap 10 is one end of a chain or other flexible medium 11' the opposite end of which extends through a tube or conduit 12 for engagement with a suitable locking member preferably disposed at the cab 5 of the locomotive and within convenient reach of the engineer or fire-man.

The locking member consists of a hook 13 one end of which is pivoted at 14 while the opposite end is extended to form an operating handle 15, there being a lug or projection 16 extending from the hook and adapted to receive one of the links of the chain 11' and thereby lock the spring 11 in retracted position.

Disposed one on each side of the casing 9 and secured to a vertical support or standard 90 17 are auxiliary buffers or coiled springs 18 each arranged within a suitable casing 19 and provided with a terminal head 20 similar in construction to the head or cap 10 of the main buffer. The auxiliary buffers are designed for preventing collisions with flat cars and the like and the springs of said buffers are normally held in retracted or inoperative position within the casings 19 by suitable chains or cables 21 extending through tubes 100 22 which also lead to the cab 5 of the locomotive, as shown.

As a means for simultaneously actuating the auxiliary buffers there is provided a transverse shaft 24 pivotally mounted for 105 rocking movement in suitable bearings 25 and provided with oppositely disposed hooks 26 having lugs 27 extending laterally therefrom for engagement with the links of the chains 21, so that when either of the handles 110

28 is tilted the lug 27 will be disengaged from the adjacent link of the chain and thus permit the springs 18 to project the cap 20 longitudinally of the locomotive and in the path 5 of the flat cars or other rolling stock.

Attention is called to the fact that the lugs 16 and 27 are disposed below the pivot points of the locking members so that the tension of the springs 11 and 18 will exert a longitudinal pull on said lugs and thus prevent accidental displacement of said locking members.

When it is desired to lessen the jar or shock incident to the collision with an adjacent locomotive of a train traveling in the opposite direction the engineer or fire-man tilts the handle 15 of the locking member upwardly which disengages the lug 16 from the chain 11' thereby causing the spring 11 to project the cap 10 in the path of the approaching 20 locomotive so that when the impact occurs the spring will be gradually compressed within the casing 9 and thereby lessen the jar or shock incident to the collision of said locomotives.

25 To prevent collision with flat cars and the like the handles 28 of the locking member 26 are tilted upwardly which releases the springs 18 and projects the caps 20 as shown in dotted lines in Fig. 2 of the drawing. The spring 30 will preferably be of sufficient length to prevent contact between the locomotives of adjacent trains when said springs are moved to operative or projective position and the latter will be preferably compressed within the 35 casings or housings by hydraulic or other suitable pressure.

From the foregoing description it is thought that the construction and operation of the device will be readily understood by those 40 skilled in the art and further description thereof is deemed unnecessary.

Having thus described the invention what is claimed is:

1. The combination with a locomotive, of 45 a casing secured thereto, an extensible member arranged within the casing and movable to projected position in advance of the locomotive, and a flexible medium extending longitudinally of and through the extensible 50 member for locking said member in retracted position.

2. The combination with a locomotive, of 55 a casing secured thereto, a yieldable buffer disposed within the casing and movable to projected position in advance of the locomotive, a locking member, and a flexible connection between the locking member and buffer and extending through the latter for holding the buffer in retracted position.

60 3. The combination with a locomotive, of a casing secured thereto and provided with a closure, a coiled spring disposed within the casing and operatively connected with the

closure for moving the latter to projected position in advance of the locomotive, a flexible 65 connection extending within the convolutions of the spring for holding said spring in retracted position, and a locking member engaging one end of the flexible medium.

4. The combination with a locomotive, of 70 a casing secured thereto and provided with a closure, a spring disposed within the casing and fastened to the closure, a locking member, and a flexible connection one end of which is secured to the locking member and 75 the opposite end thereof extended through the coils of the spring and operatively connected with the closure.

5. The combination with a locomotive, of 80 a casing secured thereto and provided with a closure, a spring disposed within the casing and bearing against the closure, a pivoted locking member provided with a laterally extending lug, and a chain one end of which engages said lug, the opposite end of said chain 85 being extended through the convolutions of the spring and secured to the closure.

6. The combination with a locomotive, of a casing secured to the forward end thereof and provided with a cap, a pivoted hook having its free end provided with an operating handle and its pivoted end formed with a laterally extending lug, a coiled spring disposed within the casing and bearing against the cap, and a flexible connection, one end of 90 which is secured to the cap and the opposite end thereof extended through the convolutions of the spring and operatively connected with the lug of the locking member.

7. The combination with a locomotive, of 100 a casing secured to the forward end of the locomotive and provided with a movable cap, a tube extending longitudinally of the locomotive, a pivoted locking member, and a chain, one end of which is secured to the cap, 105 the opposite end of the chain being threaded through the pipe for engagement with the locking member.

8. The combination with a locomotive, of 110 a casing secured to the locomotive and provided with a movable cap, auxiliary casings disposed one on each side of the main casing and provided with similar caps, coiled springs disposed within the casings, locking members, and a flexible medium secured to the cap of 115 each casing and extending through the convolutions of the adjacent springs for connection with the locking members.

In testimony that I claim the foregoing as my own, I have hereto affixed my signature 120 in the presence of two witnesses.

THOMAS H. HALE.
